UNITED STATES PATENT OFFICE.

FREDERICK E. KLUNKER, OF CANON CITY, COLORADO.

GRAVEL-HOPPER.

1,073,245.

Specification of Letters Patent. Patented Sept. 16, 1913.

Application filed January 27, 1913. Serial No. 744,495.

To all whom it may concern:

Be it known that I, FREDERICK E. KLUNKER, a citizen of the United States, residing at Canon City, in the county of Fremont and State of Colorado, have invented 5 certain new and useful Improvements in Gravel-Hoppers; and I do declare the following to be a full, clear, and exact description of the invention, such as will enable 10 others skilled in the art to which it appertains to make and use the same.

This invention is a feed regulator capable 15 of use in a variety of ways and in machines for widely different purposes, but employed by me in connection with a concrete mixer, and its object is to produce an improved construction of hopper whereby the gravel may be fed to the mixing machinery more or less rapidly as desired. This object is carried 20 out by constructing the hopper and its bottom in the manner hereinafter more fully described and claimed, and as shown in the drawings wherein—

Figure 1 is a side elevation of the hopper 25 and a cross section of the mixing machinery to which it delivers; and Fig. 2 is a vertical section on the line 2—2 of Fig. 1. Fig. 3 is a horizontal section on the line 3—3 of Fig. 1. Fig. 4 is a vertical section through 30 the hopper and its bottom, taken at right angles to the plane on which the section of Fig. 2 is taken. Fig. 5 is a side elevation, viewed from the reverse side from that shown in Fig. 1. Fig. 6 is a detail which 35 will be referred to hereinafter.

In the drawings I have shown my improved hopper H as mounted upon the upper end of a receptacle which in the present instance is a trough T wherein on 40 a shaft S is carried a mixer broadly designated by the letter M, but it will be obvious that this type of receptacle is shown merely for sake of illustration and my improved hopper and means for delivering the material therefrom may be attached to any form of receptacle desired.

Coming now to the details of the present invention, the hopper H has three inclined sides 1, 2, and 3, and an upright front wall 45 4, the lower portions of all its sides being also upright as seen at 5, 6 and 7 and the opposite upright side walls 5 and 7 projecting beyond the lower edge of the front wall 4 at 8 and 9. Between these projecting 55 portions is a discharge opening through which the material poured into the hopper

shall finally pass out, under the lower edge of the front wall 4, and in order to regulate its passage I provide a plate 10 having upright slots 11 in its body through which 60 pass thumb screws 12 engaging said front wall 4, so that when these screws are loosened the plate may be adjusted higher or lower in a manner which will be clear. In the illustration herewith, the hopper entire is supported on the receptacle T by means of two brackets 13 and 14 at each side, and the shape of these brackets will 65 be such that the hopper will stand above the open upper end of the receptacle but a little to one side of the same so that the material flowing out the mouth of the hopper will drop into such receptacle. In the present instance it falls into a trough-shaped receptacle and passes through the mixing 70 mechanism M, which need not be amplified as it forms no part of the present invention.

The bottom of the hopper above described is by preference made of sheet metal, and as best seen in the several views of the drawings, it comprises a plurality (such as three) 80 of steps 16, 17 and 18 connected by uprights or risers 19 and 20; upright sides 21 rising from the steps 17 and 18 or in fact from all steps excepting the highest; and horizontal 85 flanges 22 projecting straight outward from the sides 21 and passing through slots 23 in the side walls 5 and 7 of the hopper and in the extensions 8 and 9 of said walls—the slots being longer than the flanges so that 90 the entire bottom may have some degree of movement therein. In order to firmly support the bottom and the contents resting thereon, and so that said flanges will not bear frictionally on the lower edges of the 95 slots 23, I may provide rollers 24 carried by the brackets 13 and 14, or perforated ears 25 rising from the flanges 22 and sliding on guide rods 26 carried by said brackets, or both; and it will be clear that if this device 100 is used for sand and gravel and other heavy material some mechanism must be provided to prevent or to reduce the friction which would result if said flanges were in actual contact with the lower edges of the slots 23. 105

Coacting with the parts above described is mechanism for reciprocating the bottom within the slots 23, and while any suitable mechanism may be employed, I have typically illustrated one form herewith which 110 would operate successfully. That is to say, a power wheel 30 is connected by suitable

mechanism with some source of power (as the gear 31 on the shaft S of the mixing mechanism, for instance), and in this wheel is a series of holes 32 (Fig. 6) in which is adjustably mounted a wrist pin 33 which is connected by a pitman rod 34 with a pin 35 carried by a bracket 36 attached to one of said flanges 23 or to the bottom in any suitable manner. It follows that the rotation 10 of the power wheel 30 causes the reciprocation of the hopper bottom on its guides, whatever the form of the latter, and therefore the material fed into this hopper will be delivered out its mouth under the lower 15 edge of the plate 10 and over the lowest step 18 of said bottom at a speed dependent upon the position at which said plate is set, the number and vigor of the reciprocations imparted to the bottom by the crank wheel 30, and the size of the particles of material.

A further description of the operation of this device is thought to be unnecessary, and the details of its construction may be modified to an extent consistent with the following claims.

What is claimed as new is:

In a feed regulator, the combination with a receptacle, a hopper whose body has an

open bottom and a discharge opening through its front wall, the side walls of the 20 hopper being extended beyond its front wall and having horizontal slots, and a gate for adjusting the size of said opening, of a bottom made in steps descending toward and extending through said opening and 25 having upright sides and outturned flanges projecting through said slots, brackets secured to the side walls of said hopper and supporting it above said receptacle, rollers journaled in said brackets beneath said 40 flanges and holding the latter out of contact with the edges of said slots, guide rods connecting said brackets at points above the flanges, perforated ears rising from the latter and slidably mounted on said rods, a 45 bracket depending from one of said flanges, and means connected with this bracket for reciprocating said bottom.

In testimony whereof I have hereunto set my hand in presence of two subscribing witnesses.

FREDERICK E. KLUNKER.
